CLAIM

I claim the ornamental design for a mirror with a digital clock, as shown and described.

DESCRIPTION

FIG. 1 is a top plan view of a mirror with a digital clock according to the present design;

FIG. 2 is a left side elevational view of the mirror with a digital clock of FIG. 1;

FIG. 3 is a right side elevational view of the mirror with a digital clock of FIG. 1;

FIG. 4 a rear elevational view of the mirror with a digital clock of FIG. 1; and,

FIG. 5 is a front elevational view of the mirror with a digital clock of FIG. 1.

The broken lines in the digital clock are for illustrative purposes only and form no part of the claimed design.
